UNITED STATES PATENT OFFICE.

WILLIAM PRINCE-SMITH AND DAVID WATERHOUSE, OF KEIGHLEY, ENGLAND.

NOBLE'S COMBING MACHINE.

Application filed November 12, 1925. Serial No. 68,720.

To all whom it may concern:

Be it known that WILLIAM PRINCE-SMITH and DAVID WATERHOUSE, both subjects of the King of Great Britain, residing at Keighley, in the county of York, England, have invented certain new and useful Improvements in Noble's Combing Machines, of which the following is a specification.

This invention relates to Noble's combing machines and it has for its object to provide a compact and efficient driving means therefor.

To this end the invention consists of a self-contained electric driving unit so constructed and arranged as to be capable of attachment directly to existing combing machines without necessitating any important or complicated structural alterations thereto.

The invention comprises a specially shaped base-plate constructed so as to fit directly on to the ordinary pillars of a Noble's combing machine and carrying an electric motor whereof the spindle is put into direct driving connection with the usual cross-shaft of the combing machine.

One convenient form of drive is by means of an endless chain engaging a sprocket on the motor spindle and another sprocket secured to the aforesaid cross-shaft; said chain being enclosed in a casing forming one with or attached to said base plate.

The base plate may be attached to the tops or the sides of the pillars of the machine.

The invention is illustrated by way of example in the accompanying drawings which show only so much of a Noble's combing machine as is necessary to indicate the attachment thereto of the electric driving mechanism.

Figure 1 is a side elevation showing the base-plate and attached electric motor mounted upon the usual pillars of the machine.

Figure 2 is a plan view of the base-plate with the motor removed.

Figure 3 is an end view, partly in section, of the driving connection between the motor and the combing machine.

As will be seen by reference to Figure 2 the base plate A consists of a casting whereof the configuration is such that the base plate is adapted to seat on the tops of the usual pillars B, B, of the machine, by virtue of circular rims A¹, A¹, formed integrally

with said base plate. Intermediately of said rims A¹, A¹, the base plate is formed as a platform having slotted and machined surfaces A², A², for the reception of the pedestal or feet of an electric motor C which is bolted thereto.

The baseplate A is formed with a rectangular slot A⁴.

D is a sprocket wheel keyed to the spindle C¹ of the motor C, and D¹ is another sprocket wheel keyed to the usual cross-shaft E of the combing machine, F being an endless chain engaging said sprocket wheels and being tensioned by a jockey sprocket-wheel G carried by a spindle mounted adjustably on the casing H which is formed integrally with or may be attached to the base plate A; said endless chain F passing through the aforesaid slot A⁴ in the base plate.

The jockey sprocket-wheel G may be adjusted by means of a milled nut G¹ carried by a screwed eyebolt G² engaging the spindle G³ of the sprocket G.

A cover-plate (not shown) is provided for the casing H so as to enclose totally the chain drive from the motor C to the shaft E.

By means of the above described construction the usual belt-driven Noble's combing machine can easily and expeditiously be converted without necessitating structural alterations other than substituting a sprocket wheel for the usual fast and loose pulleys on the cross-shaft, and an efficient and compact direct form of drive is secured.

What we claim is:

1. Driving means for a Noble's combing machine having pillars, comprising a unitary structure constructed for direct attachment to said pillars and characterized by a base-plate shaped so as to be complementary to said pillars, an electric motor carried by said base-plate, and means connecting said electric motor drivably with said combing machine.

2. Driving means for a Noble's combing machine having pillars and a cross-shaft, comprising a self-contained driving unit characterized by a base-plate shaped so as to be complementary to said pillars, means attaching said base-plate to said pillars, an electric motor secured to said base-plate, and a driving connection between said electric motor and said cross-shaft.

3. Driving means for a Noble's combing

machine having pillars and a cross-shaft, comprising a self-contained driving unit characterized by a base-plate shaped so as to be a complementary fitment upon said pillars, means securing said base-plate to said pillars, a transverse slot in said base-plate, surfaces upon said base-plate to receive a driving element, an electric motor secured upon said surfaces upon said base-plate, a 5 sprocket carried by said electric motor, a sprocket carried by said cross-shaft, and a driving connection between said sprockets.

4. Driving means for a Noble's combing machine having pillars and a cross-shaft, comprising a self-contained driving unit characterized by a base-plate shaped so as to be a complementary fitment upon said pillars, means securing said base-plate to said pillars, a transverse slot in said base-plate, surfaces upon said base-plate to receive a driving element, an electric motor secured upon said surfaces upon said base-plate, a sprocket carried by said electric motor, said sprocket being located above said 10 slot in said base-plate, a second sprocket carried by said cross-shaft, said second sprocket being located below said slot in said base-plate, and a driving connection between said sprockets.

5. Driving means for a Noble's combing machine having pillars and a cross-shaft, comprising a self-contained driving unit characterized by a base-plate shaped so as to be a complementary fitment upon said pillars, means securing said base-plate to 30

said pillars, a transverse slot in said base-plate, surfaces upon said base-plate to receive a driving element, an electric motor secured upon said surfaces upon said base-plate, a sprocket carried by said electric motor, said sprocket being located above said slot in said base-plate, a second sprocket carried by said cross-shaft, said second sprocket being located below said slot in said base-plate, an endless chain connecting 40 said sprockets drivably, and means enclosing said endless chain.

6. Driving means for a Noble's combing machine having pillars, and a cross-shaft, comprising a self-contained driving unit characterized by a base-plate shaped so as to be a complementary fitment upon said pillars, means securing said base-plate to said pillars, a transverse slot in said base-plate, surfaces upon said base-plate to receive a driving element, an electric motor secured upon said surfaces upon said base-plate, a sprocket carried by said electric motor, said sprocket being located above said slot in said base-plate, a second sprocket 50 carried by said cross-shaft, said second sprocket being located below said slot in said base-plate, an endless chain connecting said sprockets drivably, and a casing borne by said base-plate and totally enclosing said 55 sprockets and said endless chain.

In testimony whereof we affix our signatures.

WILLIAM PRINCE-SMITH.
DAVID WATERHOUSE.
